T. J. AUSTIN.
GATE.

No. 439,460.

Patented Oct. 28, 1890.

UNITED STATES PATENT OFFICE.

THOMAS J. AUSTIN, OF BELLE PLAIN, TEXAS, ASSIGNOR OF ONE-HALF TO
EDMOND A. HEARN AND ROBERT B. HEARN, BOTH OF SAME PLACE.

GATE.

SPECIFICATION forming part of Letters Patent No. 439,460, dated October 28, 1890.

Application filed March 18, 1890. Serial No. 343,813. (No model.)

To all whom it may concern:

Be it known that I, THOMAS J. AUSTIN, of Belle Plain, in the county of Callahan and State of Texas, have invented certain new and useful Improvements in Gates; and I do hereby declare that the following is a full, clear, and exact description thereof, reference being had to the accompanying drawings, and to the letters of reference marked thereon, which form a part of this specification.

My invention relates to gates, and has for its object to provide an improved gate which is strong, durable, economical of manufacture, and reliable in operation; and to these ends the said invention consists in the novel construction and new combinations of parts, as hereinafter described and claimed, reference being had to the accompanying drawings, in which—

20 Figure 1 is a perspective view showing my improved gate in its closed position. Fig. 2 is a front view of the same in its open position, omitting for the sake of clearness the outlying standards. Fig. 3 is a detail vertical 15 central section. Fig. 4 is a view showing a portion of the endless chain, and Fig. 5 is a detail view of the latch.

In the said drawings, the reference-letters B designate vertical posts or standards, to the 25 upper ends of which is bolted or otherwise 30 sustably secured the horizontal beam or bar C.

The letters C' indicate top rails or bars, depending from which are the gate-sections D, and extending upwardly from which are 35 brackets H, in which are journaled friction-rollers I, said rollers traveling on any suitable track (not shown) on the upper surface of the beam or rail C.

Secured at one end to the vertical standards 40 and at the other to the cross beam or bar C are yokes or stirrups G, each of which is provided with an axis S, upon which is journaled a pair of pulleys E.

Within each yoke or stirrup G and arranged 45 between the pulleys E is a spur-wheel F, upon which travels the endless chain J. These pulleys E and spur-wheels F are either made integral or are securely fastened together in order that they may move in unison, as may 50 be found preferable. The chain J is con-

nected with the two inner brackets H by a link, as shown, or other suitable means, one of said brackets being extended in order that it may be connected to that part of the endless chain which is uppermost as it lies upon the spur-wheels F.

To the standards B are secured brackets T, each of which is provided with a series of three horizontal arms, between which are arranged two pulleys T', one above the other. 60

Arranged at a suitable distance from the gate, at each side thereof, are four posts or standards lettered K, to the upper ends of which are secured brackets L, within which are arranged pulleys L'. 65

Secured at one end to each of the four pulleys E is a cord, chain, or wire n, which cords are wound around said pulleys several times, (according to the distance traveled by the gate-sections in opening and closing,) then 70 passed around their respective pulleys T', and thence over their respective pulleys L'. The two cords for operating each gate-section are wound in reverse directions upon the corresponding pulleys E, so that a pull upon one 75 of the cords will cause the gate to open, while a pull upon the other will close the same. To the ends of said cords, chains, or wires, opposite the ends secured to the pulleys E, are secured counter-weights N', the object of which 80 is to retain the cords, chains, or wires in a taut condition and to afford a convenient hand-hold.

The letters R indicate any suitable guides for the bottom edges of the gate-sections. 85

To one of the gate-sections is secured a latch P, consisting of a vertical arm, preferably extending through an orifice in the top rail or bar C' and engaging with the endless chain J, and a lateral extension having a lug to engage a suitable device on the other gate-section. The said latch is thrown into locking engagement, and there normally held by a suitable spring O, as shown.

In Fig. 4 I have shown the preferred form 95 of chain L, in which the links are in form somewhat acute-angled, and each link is open at one end and its ends are turned into engagement with the next following link.

The operation on my improved gate is as 100

follows: To open the gate, the operator pulls the cord n , (at the right-hand side of the gate, for example,) which causes the pulleys E, to which it is attached, and at the same time 5 the spur-wheels F to revolve, the latter operating the endless chain, whose initial movement throws the vertical arm of the catch P and releases the gate-sections, whereby said gate-sections are caused to move in opposite 10 directions by reason of their connection—one with the uppermost and the other with the lowermost portion of the endless chain—as it lies on the spur-wheels F, as hereinbefore described. After the operator has passed 15 through the gate he operates the corresponding cord n , and the gate is closed through the same instrumentalities by reason of this cord being wound on the pulley E in a direction the reverse of that which was operated to open 20 the gate. It will be observed that should either of the ropes for operating the gate-sections become broken the construction is such that the connection between the gates will remain unimpaired, and until the broken rope 25 is replaced the gates can be operated in that direction by hand.

Gates of this class have heretofore been operated by an endless rope running over a series of pulleys, said rope having an attached 30 handle, which is moved toward and from the gate to operate the same. In this construction if the handle nears the pulleys the power becomes weakened, and the handle is also liable when the rope becomes slack by reason 35 of rain to work under the pulleys, thus obstructing its free operation. Again, in such gates it is necessary to have out-posts at a

considerable distance from the gate, according to the distance the gate-sections are to move in opening and closing, and the operator is obliged when opening the gate to move a considerable distance. All these objections are avoided by my invention, which provides a gate which is durable, economical, and effective in operation. 40 45

What I claim is—

1. In a gate, the combination of a top beam or bar supported upon vertical standards, gate-sections hung thereupon, the pulleys E, the spur-wheels F, the endless chain thereon 50 connected with the gate-sections, the horizontal pulleys T', and the cords n , wound in reverse directions upon said pulleys E, substantially as described.

2. In a gate, the combination of vertical 55 standards, a top beam or bar supported thereby, gate-sections, brackets H, secured to the top rails of said gate-sections, friction-rollers journaled in said brackets and moving on the said top beam or bar, brackets secured to said 60 vertical standards, pulleys and spur-wheels E and F, journaled therein, an endless chain upon said spur-wheels connected to the two inner of said brackets H, horizontally-arranged pulleys T', journaled in brackets secured to said vertical standards, the posts K, having pulleys L', and the cords n , passing over said pulleys L' and T' and wound in reversed directions upon the pulleys E and 65 secured thereto, substantially as described.

THOMAS J. AUSTIN.
